DESIGN FOR A COSMETIC HOLDER

Emil H. Orenick, Cleveland, Ohio

Application October 26, 1948, Serial No. 149,307

Term of patent 14 years

(Cl. D86—10)

To all whom it may concern:

Be it known that I, Emil H. Orenick, a citizen of the United States, residing in the city of Cleveland, county of Cuyahoga, and State of Ohio, have invented a new, original, and ornamental Design for a Cosmetic Holder, of which the following is a specification, reference being had to the accompanying drawing, forming a part thereof.

I claim:

The ornamental design for a cosmetic holder, substantially as shown.

EMIL H. ORENICK.
